UNITED STATES PATENT OFFICE.

BENJAMIN S. McCLELLAN, OF CHICAGO, ILLINOIS, ASSIGNOR TO GRIP NUT COMPANY, OF CHICAGO, ILLINOIS, A CORPORATION OF ILLINOIS.

LOCK NUT.

Application filed August 29, 1922. Serial No. 585,031.

This invention relates to lock nuts.

One object of my invention is to deflect a portion of a number of the threads of the nut into the bore and longitudinally thereof and to increase the frictional resistance to turning the nut off a bolt and thus lock it on, by providing the deflected thread portions with abrupt ends inclined to resist the reverse turn and exert a sort of cam action at that time.

Another object of my invention is to so incline these abrupt ends and deflect the threads that no material resistance is offered to turning the nut on a bolt.

15 A further object of my invention is to accomplish this deflection and abrupt ends by punching a single notch into the nut body adjacent its bore and displacing by bending inward and downward a portion 20 of the nut body between the notch and bore.

The invention consists further in the matters hereinafter described and more particularly set forth in the annexed claims.

In the accompanying drawings—

25 Fig. 1 is a perspective view of a lock nut made in accordance with my invention;

Fig. 2 is a top plan view of said nut;

Fig. 3 is an enlarged vertical sectional view taken on line 3—3 of Fig. 2;

30 Fig. 4 is an enlarged similar sectional view taken on line 4—4 of Fig. 2, with the nut shown started on a bolt; and

Fig. 5 is a similar view with the nut completely turned on the bolt and locked in 35 accordance with my invention.

To accomplish the objects of my invention, I take a nut 1 of a standard size with screw threads 2 of a uniform diameter and pitch throughout the length of the bore 3.

40 With a punch or other tool 4, as shown in Fig. 4, I cut a single notch 5 in the metal body of the nut through its outer face 6, adjacent the edge of the bore 3 and at one place in the circumference thereof. The punch 4 is so made that the notch 5 is shaped as follows:

The bottom edge 7 is curved in an arc of a circle concentric to that of the bore 3, as shown in Fig. 2, and is inclined upward 50 from the deepest point at one end of the notch to the shallowest point at the other end, as shown in Fig. 3. The notch at its deepest end has an upwardly extending straight edge 8 inclined inward toward the bore 3, as shown in Fig. 2.

The inner and outer walls 9, 10 of said notch diverge upward from said bottom edge 7 and are thus inclined on opposite sides of said bottom edge, the inner wall 10 being inclined toward said bore 3. These 60 walls 9 and 10 are also curved eccentric to the bore 3, as indicated by their outer edges in the outer face 6 of said nut. The inner wall 10 curves inward toward the bore 3 and ends in the edge 8. The outer wall 9 has 65 a greater curvature and terminates with a sharp re-entrant curve extending toward the bore 3 to reach the edge 8.

The notch 5 so made is somewhat wedge shaped and has its widest end nearest the 70 bore 3. In punching the notch adjacent the bore 3, the metal of the nut body between the notch and the bore is displaced and forced into the bore and also downward toward the lower end thereof. This deflects the upper 75 threads 11, 11 into the bore and downward. By having the widest and deepest end of the notch 5 directed inward, the deflected thread portions terminated in abrupt ends 80 12, 12 aligned lengthwise of the bore and inclined in the direction trailing the nut on the bolt 13, the latter being shown in Figs. 4 and 5.

The approximate amount of inward deflection is indicated in Fig. 4 by the dotted 85 lines *a*, *b*, the former being parallel with the threads before deflection and the latter after. The deflected thread portions 11 as they approach the abrupt ends 12, 12 have a gradual inward and downward deflection, 90 as shown. This is due to the notch 5 having its shallowest end farthest away from the bore 3 and gradually widening toward the bore. The abrupt ends 12, 12 constitute in effect shoulders to resist any reverse turn of 95 the nut and bolt relative to each other.

The nut 1 takes easily on the bolt 13 because the threads 2 at the entrance of the bore 3 remain undisturbed and have the same diameter and pitch as the undeflected 100 portions of said deflected threads 11, 11. The nut 1 is guided on the bolt 13 like an ordinary nut. No locking takes place while the nut is turned on the bolt 13 because the deflected thread portions 11, 11 tend to 105 straighten out and offer no material resistance to the forward turning of the nut. This is due to the shoulders or ends 12 being inclined in the direction of this turn. Turning the nut 1 backward, however, causes the 110

- shoulders 12 and deflected portions 11, 11 to immediately have cam effect and lock the nut on the bolt by crowding the metal of the said portions 11 into the spaces between the 5 engaged bolt threads. This frictional resistance is increased as the leverage on the nut to back it off the bolt is increased because the abrupt shoulders 12 and deflected portions 11 increase in their cam action.
- 10 The deflected threads of the nut bring all of the thread surfaces of the nut and bolt in the plane of said deflected threads into tight contact all around except in that portion immediately following the abrupt ends 15 or shoulders 12 of said deflected threads. This provides cavities or spaces between the thread surface and allows the metal burs on these surfaces to interlock and pack and give a die action to resist the turning of the 20 nut off the bolt.

A nut made in accordance with my invention does not lock itself on the bolt while being turned on the bolt but is always ready to lock as soon as it is given the reverse or 25 backward turn, thus allowing the nut to lock at any point on the bolt. This locking increases as the tendency to back the nut off increases and thus provides a sure and positive lock. The nut therefore is particularly 30 adapted for use where excessive and great vibration is had as on railroad cars and equipment of that general nature.

While I have shown and described herein 35 in detail a lock nut of my invention, it is of course understood that the details of construction may be variously changed and modified without departing from the spirit and scope of my invention.

I claim as my invention:

- 40 1. A lock nut having screw threads in its bore, a portion of a number of said threads at one place in the circumference of the bore being deflected into the bore and longitudinally thereof, said deflected portions 45 merging into the remaining portions of said threads gradually at one end and abruptly at the other end, the balance of the threads in the bore being the same in diameter and pitch as the undeflected portions of said deflected threads.
- 50 2. A lock nut having screw threads in its bore, a portion of a number of said threads at one place in the circumference of the bore being deflected into the bore and longitudinally thereof, said deflected portions 55 merging into the remaining portions of said threads gradually at one end and abruptly at the other end, said abrupt ends being in substantial alignment lengthwise of the bore 60 and inclined to resist turning the nut off a bolt, the balance of the threads in the bore remaining the same in diameter and pitch as the undeflected portions of said deflected threads.
- 65 3. A lock nut, comprising a body portion

having a bore with screw threads therein, and a wedge shaped notch punched into the metal of said body portion through one face of the nut and adjacent the edge of the bore for deflecting into the bore and toward the 70 opposite face of the nut a portion of a number of threads at said notch by displacing in that direction the metal of the nut body between said notch and bore, said notch having its widest end next to the bore for 75 making the deflected thread portions at said notch merge abruptly and inclined into the remaining portions of said threads to resist turning the nut off a bolt.

4. A lock nut, comprising a body portion 80 having a bore with screw threads therein, and a notch punched into the metal of said body portion through the outer face of the nut adjacent the edge of said bore for deflecting into the bore and toward the lower 85 face of the nut a portion of a number of the threads at said notch by displacing in that direction the metal of the nut body between the notch and bore, said notch having its bottom edge concentric to the bore 90 and one end relatively deep and enlarged to form in the deflected threads abrupt ends inclined to resist burning the nut off a bolt.

5. A lock nut, comprising a body portion 95 having a bore with screw threads therein, and a notch punched into the metal of said body portion through the outer face of the nut adjacent the edge of said bore for deflecting into the bore and toward the lower 100 face of the nut a portion of a number of the threads at said notch by displacing in that direction the metal of the nut body between the notch and bore, said notch having its bottom edge concentric to the bore and one end relatively deep and enlarged to 105 form in the deflected threads abrupt ends inclined to resist turning the nut off a bolt, said notch having its sides diverging outward from said bottom edge and curved eccentric to said bore and one to a greater 110 extent than the other to increase the deflection of said threads toward the abrupt ends therein.

6. The combination of a bolt and a nut, 115 said nut having a portion of a number of its threads at one end of its bore and at one place in the circumference thereof deflected into the bore and toward the opposite end thereof, said deflected portions merging into the remaining portions of said threads gradually at one end and abruptly at the other 120 end, said abrupt ends being in substantial alignment lengthwise of said bore and inclined to resist turning said nut off the bolt by frictional contact with the threads of 125 the bolt.

7. The combination of a bolt and a nut, 130 said nut comprising a body portion having a threaded bore therein and a notch punched in the outer face to form a depression ex-

tending concentric with the bore and to end, said abrupt ends being in substantial deflect a portion of a number of the threads alignment lengthwise of said bore and inclined to resist turning said nut off the bolt of the bore, at one place in the circumference thereof, towards the opposite end of by frictional contact with the threads of the bolt.
8 the bore, the depression being tapered longitudinally so that it is of greater width at one end than at the other, so that the deflected portion of the threads merge into the remaining portions of said threads gradually at one end and abruptly at the other

15 In testimony that I claim the foregoing as my invention, I affix my signature this 26th day of August, A. D. 1922.

BENJAMIN S. McCLELLAN.
